UNITED STATES PATENT OFFICE.

HERMANN LOTHAR WARRENS, OF EAST CROYDON, ENGLAND.

TIME-TABLE APPLIANCE AND ADVERTISING DEVICE.

SPECIFICATION forming part of Letters Patent No. 752,274, dated February 16, 1904.

Application filed February 6, 1903. Serial No. 142,060. (No model.)

To all whom it may concern:

Be it known that I, HERMANN LOTHAR WARRENS, member of the Stock Exchange, of Avondale, Addiscombe Grove, East Croydon, in the county of Surrey, England, have invented a certain new and useful Improved Time-Table Appliance and Advertising Device; and I do hereby declare the following to be a full, clear, and exact description of the invention, such as will enable others skilled in the art to which it appertains to make and use the same.

This invention relates to a contrivance which is adapted to facilitate the reference to time-tables such as are displayed on boards at railway-stations on which are printed a large number of columns of figures and one column of the names of railway-stations, the figures indicating the times of arrival or departure of each of many trains at the various stations on the line of railway included in the column of names. In consulting such a time-table great difficulty is encountered in accurately determining the time at which a train leaves one station and arrives at another without the assistance of one or both index-fingers and then with an undue effort of concentration and liability to the injury of the surface of the time-table. To eliminate this difficulty and fault, I mount the time-table in a frame within which is provided means for guiding the ends of a horizontal strip in such a manner that it remains always parallel to one line. The strip being lifted to a position immediately below the name of a station and held there, the eye will be guided along the horizontal edge of the strip and the time required to be known immediately observed. There are additional features of advantage associated with the invention, to which reference will presently be made.

The accompanying drawings show a method of construction whereby the invention may be carried into practical effect.

In the drawings, Figure 1 is a front elevation of the time-table and frame within which it is mounted. Fig. 2 is a sectional side elevation taken through the line 2 2 on Fig. 1. Fig. 3 is a plan. Figs. 4, 5, and 6 are enlarged views showing details of the construction, Fig. 5 being a front view of the upper right-hand

corner of the frame with a portion removed to exhibit the interior. Fig. 4 is a section through the line 4 4 of Fig. 5, and Fig. 6 is a section through the line 6 6.

For the purpose of rendering a clearer illustration the scantlings of the frame in Figs. 1, 2, and 3 are exaggerated relatively to the area of the time-table which is exhibited.

On account of the small print which is perforce adopted in order to exhibit a very large number of trains on a sheet of limited area it is necessary that the moving strip should maintain its parallelism with considerable accuracy and move with freedom even if the moving force is applied at one end and not in the center of its length. This is effected by securing each of the two ends of the strip *a* to an endless chain *b*, which at the top is wrapped around a sprocket-wheel *c*, which has teeth adapted to suit the pitch of the chain *b*, and at the bottom around a pulley *d* of plain periphery.

The two wheels *c* are identical in size and in the number of teeth, and they are secured to a spindle *e*, mounted in bearings *f f* in the upper portion of the frame. By means of this mechanism the strip can be caused to move with great freedom and remain always parallel to the top and bottom edges of the frame. The ends of the strip are guided in a narrow slit *g*, formed between the front surface of the frame, and a plate *h*, which is fastened to the front at the top and bottom. Behind the plate *h* a space is left for the edge of the time-table.

The time-table should preferably be printed on a thin card, which can be inserted through a slit *k*, formed in the top of the frame. After adjusting the card with its printed lines parallel to the movable strip, a finger and thumb recess *m* being formed in the upper surface of the frame for the purpose, the card is secured by pinching its upper edge tightly between the front lath *n*, which has sufficient flexibility for the purpose, and the back *o*. This is effected by two hinged clamps *p p*.

When the clamps are lifted, as shown in Fig. 6, the slit *k* is wide enough for the easy insertion of the time-table card, and when the clamps are pressed tightly down the wedge-

100

shape end draws the lath n toward o by pressing on the edge of a plate q , which is fastened by screws to the lath n .

To assist the observer in seeking the required information, the edge of the strip is divided into spaces which correspond to the columns of train times, and the spaces carry numerals like those at the head of the columns which signify the number of the train. In this way 10 it will be easy to identify any train.

The motion of the chain will permit of the association of another device for affording information consisting of an endless traveling band r , which is secured to the chain at a suitable portion of its length and wrapped around a semicylindrical surface s at the top, which shrouds the sprocket-wheel, and around a similar surface at the bottom, which shrouds the pulley d . By this contrivance the band will 15 be caused to move with the chain each within one side of the frame. At some suitable position a glazed window t is provided on each side of the frame, and on the band are displayed advertisements or any kind of information thought desirable—as, for example, the names of and particulars relating to hotels in the various places on the line of railway to which the time-table relates. The band should be so adjusted relatively to the chain that the 20 names of hotels or other matter which at any moment appear at the window should relate to that place on the railway whose name is most adjacent to the moving strip. The remainder of the surface of the frame may also 25 be utilized for advertisement purposes or for giving other information by providing grooves u at the front edges, as shown in the several figures, into which printed cards or plates may be slid endwise. At the bottom 30 right-hand corner is shown a secret device for preventing the card from being withdrawn by unauthorized people who are ignorant of the device. A plate v has a slotway w formed in it, into which the head of a screw fits. By 35 this means the turned-over edge of the plate v may be withdrawn sufficiently to permit the card to be extracted or one inserted. When the plate is home in place, its turned-over edge will cover the edge of the card and no 40 means for extracting it will be apparent.

The movement of the strip α may be still further utilized to effect, by lifting the strip, the automatic electric illumination of the time-table at night during the few moments 45 when it is being consulted and the extinguishing of the light by breaking the circuit when the inspection is completed by letting the strip α descend by its weight and press on the

push x of any electric switch and break the contact between the end of the spring y and 60 the contact-plate z .

I claim—

1. A device for facilitating a reference to a mounted time-table consisting of the time-table, a frame, a spindle to which sprocket-wheels are secured at the two ends thereof, two endless chains each embracing a sprocket-wheel and a pulley and extending along and within one of the sides of the frame and a strip which at each end is secured to the chain 70 and is moved therewith in such a way as to remain always parallel to one line.

2. A device for facilitating a reference to a mounted time-table consisting of the time-table, a frame which is adapted to clamp the 75 edge of the time-table and secure it in position, a spindle to which sprocket-wheels are secured at the two ends thereof, two endless chains each embracing a sprocket-wheel and a pulley and extending along and within one 80 of the sides of the frame and a strip which at each end is secured to the chain and is moved therewith in such a way as to remain always parallel to one line.

3. A device for facilitating a reference to a 85 mounted time-table, consisting of the time-table, a frame, a horizontal spindle mounted within the upper edge of the frame to which sprocket-wheels are secured at the two ends thereof, two endless chains each embracing a 90 sprocket-wheel and a pulley and extending along and within the vertical sides of the frame, a horizontal strip which at each end is secured to a chain and a band carrying advertisements which travels with the chain and 95 exposes changing portions bearing information relating to the locality the name of which is at the instant adjacent to the strip.

4. A device for facilitating a reference to a mounted time-table consisting of the time-table, a frame and a strip which is adapted to be moved within the limits of the frame in such a way as to remain always parallel to one line, and an electric switch which is adapted to be spring-pressed to close the circuit of 100 an adjacent electric lamp and when pressed by the otherwise unsupported weight of the strip to cause the circuit to be broken.

In testimony whereof I have hereunto set my hand in the presence of two subscribing 110 witnesses.

HERMANN LOTHAR WARRENS.
